UNITED STATES PATENT OFFICE

102,632

DESIGN FOR A GAS ADMINISTERING MACHINE

Jay A. Heidbrink, Minneapolis, Minn.

Application December 7, 1935, Serial No. 59,951

Term of patent 14 years

To all whom it may concern:

Be it known that I, Jay A. Heidbrink, a citizen of the United States of America, residing at Minneapolis, in the county of Hennepin and State of Minnesota, have invented a new, original, and ornamental Design for Gas Administering Machines, of which the following is a specification, reference being had to the accompanying drawings, forming part thereof, in which Fig. 1 is a front elevational view of a gas administering machine showing my new design. Fig. 2 is a top plan view with part of the base portion broken away. Fig. 3 is a side elevational view with cylindrical containers broken away.

I claim:

The ornamental design for a gas administering machine, as shown and described.

JAY A. HEIDBRINK.
